UNITED STATES PATENT OFFICE

MONROE HARRISON, OF CHICAGO, ILLINOIS

DESIGN FOR A PORTABLE DISPENSING CAR OR ANALOGOUS DEVICE

Application filed April 28, 1933. Serial No. 47,931. Term of patent 7 years.

To all whom it may concern:

Be it known that I, MONROE HARRISON, a citizen of the United States, residing at Chicago, in the county of Cook and State of Illinois, have invented a new, original, and ornamental Design for Portable Dispensing Cars or Analogous Device, of which the following is a specification, reference being had to the accompanying drawing forming a part thereof.

In the drawing:

The single view is a perspective view looking from one side and showing my new dispensing car.

What I claim is:

The ornamental design for a dispensing car or analogous device, as shown.

MONROE HARRISON.
